H. C. DAVIS.

FEED WATER HEATER, EVAPORATOR, AND THE LIKE.

APPLICATION FILED SEPT. 19, 1918.

1,372,010.

Patented Mar. 22, 1921.

UNITED STATES PATENT OFFICE.

HOWARD C. DAVIS, OF ELIZABETH, NEW JERSEY, ASSIGNOR TO AMERICAN MARINE EQUIPMENT CORPORATION, OF NEW YORK, N. Y., A CORPORATION OF DELAWARE.

FEED-WATER HEATER, EVAPORATOR, AND THE LIKE.

1,372,010.

Specification of Letters Patent. Patented Mar. 22, 1921.

Application filed September 19, 1918. Serial No. 254,807.

To all whom it may concern:

Be it known that I, HOWARD C. DAVIS, a citizen of the United States, and a resident of Elizabeth, in the county of Union and State of New Jersey, have invented certain new and useful Improvements in Feed-Water Heaters, Evaporators, and the like, of which the following is a specification.

The invention pertains more particularly to feed-water heaters, and the object of the invention is to provide a highly efficient feed-water heater adapted to receive and permit the passage through it of exhaust steam for thereby imparting heat therefrom to feed-water passing through tubes arranged within the shell of the heater and exposed to the steam.

I present my invention herein as embodied in a feed-water heater adapted to receive all of the exhaust steam from the hoisting engines, dynamos, pumps, steering engines and other auxiliary engines to be found on modern steamships and to utilize the same in heating the water fed to the boilers.

One special purpose of the invention is the provision of novel banks of tubes through which the feed-water passes and which tubes are straight as distinguished from being in the form of helical coils. The tubes of the feed-water heater of my invention are preferably horizontally disposed and are approximately of crescent or kidney bean shape in cross-section, one side of the tube having a curved longitudinal depression or indentation extending practically the full length thereof, and this indentation instead of being parallel with the axis of the tube, extends spirally around the same. The type of tube embodied in my invention is a straight tube having a spiral depression or indentation, and one purpose of this type of tube is to give the water a rotative motion when passing through the same, to increase the efficiency of the tube as a heat transmitter and to provide a tube permitting of the use of an internal scraper for cleaning the same.

My invention will be understood from the detailed description hereinafter presented, reference being had to the accompanying drawings, in which:

Figure 1 is a vertical longitudinal section through a feed-water heater constructed in accordance with and embodying my invention;

Fig. 2 is a vertical transverse section through the same, taken on the dotted line 2—2 of Fig. 1, and

Fig. 3 is a vertical transverse section on a larger scale, through one of the tubes.

In the drawings, 10 designates the shell of the heater, 11 the inlet for exhaust steam to said shell, 12 the outlet or drain therefrom, 13 a head bolted to and closing one end of said shell, and 14 a head closing the other end of said shell and comprising a tube plate 15, an outer plate or head 16 and a ring 17 interposed between said parts 15, 16 and having an inlet 18 for water and an outlet 19 for the water after the same has become heated. A partition 20 subdivides the chamber formed by the ring 17 and plates 15, 16 into an inlet chamber 21 and an outlet chamber 22. The head 14 may be variously formed to provide the inlet chamber 21 and outlet chamber 22, but the construction shown is one which it is convenient to provide and is durable and efficient.

Within the shell 10 are concentric rows or banks of straight tubes 23 which are parallel with one another and secured at one end in the plate or sheet 15 and at the other end in a plate 24 to which a head 25 is secured and which, with the plate 24, forms a header into which the water from the tubes, connected with the inlet chamber 21, may flow and from which said water may escape into the tubes 23 connected with the outlet chamber 22, the water being thus compelled to pass from the inlet chamber 21 through all of the lower tubes 23 and then return through all of the upper tubes 23 to the outlet chamber 22. Instead of the water entering through the inlet 18 and thence passing through the tubes and to the outlet 19, a reverse operation may take place, the water being admitted at 19 and thence caused to travel through the tubes and find an outlet at 18. The tubes 23, plates 24, 25 and plate 15 constitute a self-contained structure or unit which may be applied to position in the shell 10, the same being slid into the shell until the plate 15 abuts against the flange at the outer end of the shell, as shown in Fig. 1. The plates 24, 25 constitute an inner header for the tubes 23 and it is centered between lugs 26 cast on the shell 10, an open space, except at said lugs, being left around the periphery of the plates 24, 25 for the passage of steam, so that the steam may enter

the head 13 and impart its heat to the plate 25 and to the water flowing against the same.

The tubes 23 are of special construction in that they are straight and parallel with one another and that each contains a spiral depression or indentation 27 extending around the same, the special formation of the tube in cross-section being shown in Fig. 3. The shape in cross-section of each tube 23, along 10 the line of its length, is approximately of crescent or kidney-bean outline, as would be formed if a perfectly round tube were depressed inwardly along a spiral line to form a groove in the tube. The tubes 23 15 of the special shape shown impart a rotative motion to the water passing through them and impart the maximum degree of heat to the water, this increase of heat being due to the decrease in the cross-sectional area 20 of the tubes and the consequent increase of the velocity of the water flowing through the tubes. The tubes having the spiral groove or depression 27 will shed water, thus avoiding any reduction in the efficiency of the 25 tube which might take place if water remained in the groove or indentation 27. The tubes 23 by being straight, although having the spiral groove or indentation, will permit of the use of an internal scraper for cleaning 30 the same, and this is a feature of great advantage which would not be attained if the tubes were spirally coiled. The tubes may also be drawn by the tube-mills at no appreciable cost above that of drawing regular 35 tubes. The great efficiency of the type of tubes 23 permits of the construction of a highly efficient feed-water heater without an excessive number of tubes, and this results in a reduction in the number of tube-joints 40 in the plates.

In the employment of the invention the steam is admitted at the inlet 11 and fills the shell 10 around the tubes 23 and plate 25, and the drain is through the outlet 12. 45 The water is admitted to the chamber 21 and flows thence through the tubes 23 con-

nected with said chamber and thence to the chamber within the head 25, whence it returns through the tubes 23 running to the chamber 22, said water being heated in 50 transit by the steam filling the shell 10. Instead of the water passing from the chamber 21 through the lower tubes 23 and returning through the upper tubes 23 to the chamber 22, it may be found desirable to use the 55 chamber 22 as an inlet chamber for water and causes the water to flow through the upper tubes 23 to the chamber in the head 25 and then return through the lower tubes 23 to the chamber 21, which will then constitute an outlet chamber for the water. 60

The construction as a whole has been designed with the view of producing a feed-water heater of increased efficiency and one capable of being readily constructed and 65 cared for.

What I claim as my invention and desire to secure by Letters Patent, is:

1. In apparatus of the character described comprising a chamber having inlet and outlet connections, a bank of straight tubes in communication with said connections and having a longitudinal indentation in the side thereof forming a groove extending spirally around the tube. 70

2. In apparatus of the character described comprising a horizontal shell having an inlet and an outlet for steam and inlet and outlet connections for the flow of water, a bank of straight horizontal parallel tubes in 80 communication with said water connections and having a longitudinal indentation in the side thereof forming a groove extending spirally around the tube. 75

Signed at New York city, in the county 85 of New York and State of New York, this 11th day of September, A. D. 1918.

HOWARD C. DAVIS.
